Beulah M. Murrill, Jacksonville, N. C.

Application August 21, 1953, Serial No. 26,544

Term of patent 7 years

(Cl. D34—15)

To all whom it may concern:

Be it known that I, Beulah M. Murrill, a citizen of the United States, residing at Jacksonville, county of Onslow, State of North Carolina, have invented a new, original, and ornamental Design for an Animal Pull-Toy or Similar Article, of which the following is a specification, reference being had to the accompanying drawing, forming a part hereof.

Figure 1 is a front perspective view of an animal pull-toy or similar article, showing my new design; and

The broken line showing of numerals and letters around the base for illustrative purposes only.

I claim:

The ornamental design for an animal pull-toy or similar article, as shown and described.

BEULAH M. MURRILL.
